UNITED STATES PATENT OFFICE.

CHARLES J. BOGUE, OF NEW YORK, N. Y.

DYNAMO-REGULATOR.

SPECIFICATION forming part of Letters Patent No. 488,261, dated December 20, 1892.

Application filed February 18, 1892. Serial No. 421,952. (No model.)

To all whom it may concern:

Be it known that I, CHARLES J. BOGUE, of New York, county and State of New York, have invented a certain new and useful Improvement in Dynamo-Regulators, of which the following is a specification.

This invention relates to automatic regulators for dynamo electric machines and it consists of pole pieces movable circumferentially relatively to the armature.

I will describe a regulator embodying my improvement and then point out the novel features in claims.

In the accompanying drawings, Figure 1 is a side elevation, partly in section, of a dynamo embodying my improvement. Fig. 2 is a transverse vertical section thereof and also showing an automatic cut out in position. Fig. 3 is a detail showing a field pole piece.

Referring by letter to the drawings, A designates the frame of a dynamo in which are supported the field magnets A' each consisting of a core a upon which the coils a' are wound, and a segmental circumferentially movable pole piece A². Each pole piece is substantially in the form of a crescent and may have a longitudinal rib a³ formed on its rear surface adapted to engage in a channel a⁴ in a block a⁴ on the core a. The opposite adjacent ends of the pole pieces A² are secured together by a plate a⁵, which may be of brass, and attached to the pole pieces by means of screws.

B designates the armature rotating within the magnetic field and carrying the commutator B'. Brushes B² are mounted on a frame B³ which is supported by the frame A and is capable of being oscillated to adjust the brushes on the commutator. As a means for oscillating the frame B³, I have shown the frame as provided with a gear b' having its shaft extending through a portion of the frame A and provided at its outer end with a crank or hand wheel b².

Having described the dynamo generally, I will now describe the means for automatically regulating the electric current.

C designates a line wire leading from one of the brushes B², and C' designates, as here shown, the return wire leading to the opposite brush B². Lamps C² are included in the circuit C C'. The line wire C has a part c

leading to an electro-magnet C³ and from this electro-magnet the wire C may lead directly to the lamps C², or as I have shown it, in Fig. 2, an automatic cut out C⁴ may be within the circuit. In this event, the wire C leading from the electro-magnet C³ extends through the electro-magnet C⁴, thence to the lamps, and the portion of the wire C leading to the electro-magnet C³ has a branch c' secured to a fixed contact piece c². In Fig. 1, I have omitted the cut out, but have shown a portion of wire c' for connection therewith. From the contact piece c², the current is through a movable contact piece c³ from which a wire c⁴ extends to the portion of the wire C, which leads from the electro-magnet C³. The movable contact c³ is secured to cores C⁵ of the electro-magnets C⁴, and obviously the circuit will be broken through the contacts c² c³, when the magnet C⁴ is energized. The electro-magnet C³ is secured to the upper portion of the frame A.

D shows a lever fulcrumed to a standard D' extending from the frame A and D² shows a rod or bar pivotally connected at one end to one end of the lever D and pivotally engaging at its opposite end, with one of the pole pieces A². As here shown a slotted arm d extends outward from a pole piece A² and the rod or bar D² is engaged with this arm by means of a pin passing through said rod or bar and through the slot in the arm d. A retracting spring d' extends from the opposite end of the lever D to the frame A, and the core D³ of the electro-magnet C³ has a pivotal engagement with the lever D between the standard D' and the rod or bar D².

The operation of the regulator is as follows: When all the lamps in a circuit are in operation, with a normal current the segmental pole pieces remain stationary. Under an increase of current, however, due to the cutting out of one or more of the lamps, the overload of current energizes the electro-magnet C³ which will draw the core D³ downward and consequently change the position of the segmental pole pieces relatively to the armature B. When the current strength is diminished, the poles will be returned to their normal position through the agency of the spring d'.

When the automatic cut-out is employed in the circuit, an overload of current will en-

ergize the magnets C⁴ and break the circuit at c² c³ and thus direct all of the current through the electro-magnet C³ and cause it to shift the pole pieces A² as before described.

5 Having described my invention what I claim is:

1. In a dynamo electric machine the combination with an armature and an electro-magnet in the circuit of said dynamo of pole pieces movable circumferentially by an over-load of current in the electro-magnet, substantially as specified.

2. In a dynamo electric machine, the combination with an armature, of circumferentially movable pole pieces, an electric circuit comprising an electro-magnet a lever operated in one direction by the electro-magnet and a connection between said lever and the

movable pole pieces, substantially as specified.

3. In a current regulator for dynamo electric machines, the combination with circumferentially movable segmental pole pieces and an electric circuit of an electro-magnet in said circuit operating to control the movements of the pole pieces and an automatic cut-out in said circuit serving to direct all of the current through said electro-magnet, substantially as specified.

In testimony whereof I have signed my name to this specification in the presence of two subscribing witnesses.

CHARLES J. BOGUE.
